UNITED STATES PATENT OFFICE.

HENRY C. HOPEWELL, OF NEWTON, MASSACHUSETTS, ASSIGNOR TO L. C. CHASE & COMPANY, OF BOSTON, MASSACHUSETTS.

CONVERTIBLE ROBE AND WRAP.

Application filed August 7, 1920. Serial No. 401,855.

To all whom it may concern:

Be it known that I, HENRY C. HOPEWELL, a citizen of the United States, residing at Newton, county of Middlesex, State of Massachusetts, have invented an Improvement in Convertible Robes and Wraps, of which the following description, in connection with the accompanying drawing, is a specification, like characters on the drawing representing like parts.

This invention relates to robes such for example as are used in automobiles and carriages and which are generally of a rectangular shape and which are made of various materials. A rug, shawl or similar article is included by the term "robe" as used in connection with this invention.

The object of the invention is to provide for the ready conversion of such a robe into a wrap which will substantially fit the person of the wearer and which conversion can be effected without cutting or changing the shape of the robe.

The object of the invention is to provide a convertible robe and wrap in which no change is made in the shape or construction of the robe and in which the robe is readily and quickly converted when desired into a wrap substantially fitting the person of the wearer simply by engagement of the members of separable fasteners.

The invention is of special use in emergencies as in the case of a person traveling unprovided with a wrap or overcoat and it enables a very satisfactory wrap fitting the person quickly and readily to be provided.

The nature and object of the invention will appear more fully from the accompanying description and drawings and will be particularly pointed out in the claim.

The invention is shown in the drawings in two forms embodying the same essential principles but differing slightly in the form of collar provided.

In the drawings—

Fig. 1 is a front view showing a robe embodying the invention converted into a wrap having a roll or shawl collar.

Fig. 2 is a side elevation of the wrap shown in Fig. 1.

Fig. 3 is a plan view of the robe showing

the position of the separable fastener members by which this robe is converted into the wraps shown in Figs. 1 and 2.

Fig. 4 is a front view showing a robe embodying the invention converted into a wrap having a stand-up collar.

Fig. 5 is a side elevation of the robe shown in Fig. 4.

Fig. 6 is a detail in cross section taken on the line 6—6 of Fig. 4.

Fig. 7 is a plan view of the robe showing the position of the separable fastener members by which this robe is converted into the wraps shown in Figs. 4, 5, and 6.

The robe, samples of which are shown in Figs. 3 and 7, may be of any suitable size and material. The ordinary automobile robe is adapted to make a wrap which corresponds to a heavy overcoat reaching nearly to the ankles of the wearer when this invention is employed.

In order to embody this invention it is only necessary to provide such a robe with a plurality of separable fasteners each comprising two members and arranged in the required positions on the robe. The term separable fastener is employed herein as a generic term to indicate any suitable device for this purpose. The ordinary button and button hole is the simplest form of separable fastener and there are a wide variety of such devices.

In the preferred constructions illustrated the separable fasteners are shown of the usual ball and socket type but the invention is independent of the particular type of separable fastener employed.

In Fig. 3 that side of the robe is illustrated which forms the outside of the wrap and if the robe has a wrong and a right side this would be the right side. In order to indicate the proper position of the members of the separable fastener they are indicated on the drawings by the following letters having the following significance.

S—representing the socket of the socket member B—representing the ball of a ball member. HS—representing the head or back of a socket member which projects from the opposite side of the robe. HB—representing the head or back of a ball

member which projects at the opposite side of the robe.

The principal feature by which the robe is converted into a substantially fitting wrap resides in the position of the separable fastener members by which a collar portion is formed which enables the robe when converted into the wrap to fit the neck and shoulders of the person. This is secured by 10 placing midway an edge such as the longer edge 1 of the robe and adjacent the edge one of the members such as a socket member 2 of a separable fastener and by placing on a line normal to the said edge extending from the member 2 the cooperating fastener member such as the ball member 3. When now these fastener members 2 and 3 are brought into engagement a fold is formed as shown at 4 in 15 Figs. 1 and 2 in the central portion of the said robe edge 1 tapering away at both sides of the medial line upon which the fastener members 2 and 3 are located to present a collar having a roll or shawl effect 20 which enables the robe to fit the neck and shoulders of a person when wearing as a wrap.

A second feature of importance enables the robe when converted into a wrap to fit the arms of the wearer. This result is secured by providing separable fasteners at each of the side edges 5 and 6 of the robe extending from the edge 1. One member of 30 each of these separable fasteners is arranged near one of each of the end corners of the said edge 1. This is shown in each case as a socket member 7 projecting from the opposite side of the robe. The cooperating members are arranged adjacent the edges 5 and 35 6 extending from the edge 1. These are shown as ball members 8 projecting from the opposite side of the robe and these members 8 are so spaced from their respective cooperating member 7 that when they 40 are engaged sleeve-like folds 9 are formed in the robe which fit the arms of the person.

A third feature which may be employed if desired enables the robe to be fastened over the front or chest of the wearer. For 50 this purpose fastener members are located at one of more points along the edge 1 at each side of the medial line and at or beyond the ends of the collar portion 4. In the construction illustrated one separable fastener comprising a ball member 10 and the socket member 11 projecting at the opposite side of the robe are shown just at the end of the collar portion 4 and a second separable fastener comprising a ball member 12 and a 55 socket member 13 projecting on the opposite side of the robe are shown further along adjacent the edge 1. Thus when the members 10 and 11 are fastened the robe will be 60

buttoned snugly about the neck of the wearer and if the members 12 and 13 are fastened 65 the robe will be buttoned over the chest.

It is found in practice that by the use of this arrangement of separable fasteners the robe is readily converted into a wrap which very substantially and closely fits the neck, 70 shoulders, and arms of a person and which if desired may be fastened at the front producing a very satisfactory substitute for an overcoat.

The construction illustrated in Figs. 4 to 75 7 of the drawings is in most respects similar to that already described. The only differences are first in the arrangement of the separable fasteners by which a thicker collar having a stand-up effect is produced and, 80 second, the arrangement of the fasteners at the front by which the wrap may be fastened in the opposite direction from that shown in Figs. 1 to 3.

In this construction the members of the fastener by which the collar is formed are shown as a socket member 14 and a ball member 15. The outer or socket member is spaced from the edge 16 of the robe at a distance corresponding substantially to the desired height of the collar at the back and the inner or ball member 15 is spaced from the socket member 14 a distance which is substantially twice the distance the socket member 14 is spaced from the edge 16. 90 95

Consequently when these members are brought into engagement as shown in Fig. 6 the central portion of the edge of the robe is formed into a collar portion 17 having three thicknesses of the robe material and 100 presenting a stand-up effect.

The fastener members 18 and 19 are shown as socket members projecting on the opposite side of the robe and cooperating respectively with ball members 20 and 21 105 so that when the robe is fastened at the front as shown in Fig. 4 it is fastened with the left hand side foremost.

The arrangement of the separable fastener members by which the folds forming 110 the sleeves are formed is the same as that already described.

Having thus described my invention what I claim as new and desire to secure by Letters Patent is—

A robe having the two members of a separable fastener arranged adjacent and midway one of the edges and on a line normal to the said edge and so positioned that by the engagement of said fastener members alone 120 a fold is formed in the central portion of said robe edge tapering away at both sides of said medial line to present a collar, a second separable fastener having its two members arranged adjacent the said edge beyond the collar portion and at opposite sides 125

of the said medial line, a pair of separable fasteners having one member of each arranged near the end corners of said edge and the other cooperating member of each ar-

5 ranged adjacent the edges extending from said corners and so spaced that when the said members are respectively engaged

sleeve like folds are formed in the robe thus enabling the robe to fit the neck, shoulders and arms of a person and be worn as a 10 wrap.

In testimony whereof, I have signed my name to this specification.

HENRY C. HOPEWELL.
